UNITED STATES PATENT OFFICE

2,162,065

PAINT ADVERTISING DEVICE

Wilbur J. Dallinger, Atlantic, Iowa

Application July 18, 1938, Serial No. 219,808

12 Claims. (Cl. 40—139)

An object of my invention is to provide a paint advertising device of simple, durable and inexpensive construction which is designed and operated so as to have a spectacular appeal to the observer.

Still a further object is to provide a paint advertising device comprising a background element which shows a house or the like, and to provide apparatus for supporting a paint brush so that its bristles are apparently painting the surface of the house, mechanism being provided to oscillate the paint brush in a curved line with the brush standing out from the surface of the house in the same position and so that it performs exactly the same as though an operator had stepped up to the picture and started to paint it and then withdrew his hand leaving the brush to continue to perform by itself, the mechanism for operating the brush being entirely concealed from view.

Still a further object is to provide apparatus for causing the brush to sweep back and forth across a background, a color wheel or the like cooperating with the brush so that the brush apparently paints out one color and paints on an other color when traveling across the background in one direction.

A further object is to provide apparatus which is preferably motor driven for operating the brush and color wheel in synchronism so that the illusion of a self painting brush is complete in all details.

With these and other objects in view, my invention consists in the construction, arrangement and combination of the various parts of my paint advertising device, whereby the objects contemplated are attained, as hereinafter more fully set forth, pointed out in my claims, and illustrated in the accompanying drawing, in which:

Figure 1 is a perspective view of a paint advertising device embodying my invention.

Figure 2 is a front elevation of my apparatus with the background element (shown as a picture of a house in Figure 1) removed.

Figure 3 is a rear elevation of Figure 2.

Figure 4 is a sectional view on the line 4—4 of Figure 3, except that a color wheel of the apparatus is shown in plan view.

Figure 5 is a plan view of the paint brush supporting mechanism looking in the direction of the arrow 5 adjacent Figure 2.

Figure 6 is an enlarged sectional view on the line 6—6 of Figure 5 showing a tripping means for the paint brush supporting mechanism, the lower half of the figure being an enlarged elevation of a portion of Figure 3.

Figure 7 is an enlarged sectional view on the line 7—7 of Figure 1;

Figure 8 is a sectional view on the line 8—8 of Figure 5; and

Figure 9 is a perspective view of a detail of applicant's invention.

On the accompanying drawing I have used the reference numeral 10 to indicate a box-like support for the apparatus of my paint advertising device. Frame bars 12 extend therefrom and support a backboard 14. Against the backboard 14, a background element 15 of sheet metal or cardboard is secured as by molding members 16 around the edge of the backboard. These molding members may be hingedly connected by spring hinges 17 to a reinforcing frame 13 of the backboard 14 so that the molding members can be swung back as shown by dotted lines in Figure 7 to permit changing of the background elements 15.

A plurality of the background elements having different pictorial representations thereon, such as, houses, barns, room interiors or the like are preferably provided to permit changing the display. Below the background element 15, a card or sign 18 may be positioned in the frame 13 for indicating to the public the particular "special" being advertised.

The backboard 14 and the background element 15 are provided with slots 14a and 15a (see Figure 8) into which the bristles 19 of a paint brush 20 extend. The paint brush is supported by a Z shaped rod having portions 21, 22 and 23 (see Figure 8). The portion 21 is concealed by the bristles 18 and the portion 22 is pivotally mounted in a sleeve 24. The sleeve 24 is supported by a triangular plate 25 across the upper surface of which the portion 23 of the rod is adapted to swing. A weight 26 is provided on the portion 23 and the swinging of the portion 23 is limited by a strap 27.

The triangular plate 25 is supported by a rod 28 pivoted at 29 to the top of the support 10. The arm 28 and thereby the plate 21 are oscillated through an arc of a circle by a reciprocating bar 30, link 31 and crank disk 32. The crank disk 32 is driven by a gear reducer 33 which in turn is driven by an electric motor 34. An operative connection is provided between the reciprocating bar 30 and the oscillating arm 28 which consists of a block 35 slidable on the arm and pivoted as at 36 to the bar.

A color wheel 37 is rotatably mounted on a shaft 38. A plurality of arc shaped sections A, B, C, D and E are detachably mounted thereon by positioning their ends between inner clips 39 and outer spring clips 40. The sections A, B, C, D and E are preferably of different colors and interchangeable for the purpose of using different color combinations depending on the colors of paints being advertised.

The color wheel 37 is rotated step by step a fifth of a revolution at each step by the following described mechanism. An arm 41 is pivoted at

42a and oscillated by the reciprocating bar 30 in the same manner as the arm 28 by a sliding block 35a pivoted at 36a to the bar in the same manner as the sliding block 35 and its pivot 36. The outer end of the arm 41 is provided with an actuating pawl 42 engageable with lugs 43 spaced around the color wheel 37 and secured to an annular reinforcing flange 37a thereof.

A pair of catches 44 (see Figure 6) are cooperable with the portion 23 of the Z-shaped rod which supports the paint brush 20. The catches 44 are mounted on leaf springs 45 and are releasable by a lever 46 and links 47. The lever 46 is secured to a rock shaft 48 to which is secured a lever 49 having a pair of flanges 50. A lever 51 is pivoted at 52 to the arm 28 and is adapted to strike stop flanges 53 (see Figure 3) during the oscillation of the arm 28. The lever 51 has its upper end located between the flanges 50.

20   Practical operation

In the operation of my paint advertising device, suppose that a merchant wishes in his paint or window display to feature certain outside paints of various colors which he carries in stock. First he selects his color sections or cards A, B, etc., to correspond with the particular colors of paint he wishes to advertise. These cards may be made of Celluloid or the like and are readily interchangeable by manipulating the spring clips 40. After the color cards are mounted he proceeds to select a suitable background element 15, several of which he would have in stock for the purpose of changing to any particular special he wishes to put on. These are preferably beautifully colored for attraction and the arc-shaped slot 15a is arranged at a conspicuous place in the picture. The molding members 16 may be turned back as shown in dotted lines in Figure 7 to facilitate changing the background elements 15 and the sign elements 18 which have different appropriate wordings.

When the motor 34 is thereafter energized, the arm 28 will oscillate substantially the length of the slot 15a and carry with it the paint brush 20. As the paint brush is oscillated toward the right, it will be inclined as shown by solid lines in Figure 5 until it reaches the right hand end of the slot whereupon its inclination will be reversed as shown by dotted lines. Such reversal of the inclination is accomplished by the lever 51 striking the right hand stop flange 53 when the dotted line position of Figure 3 is reached. This causes the rock shaft 48 to rotate counter-clockwise and release the left hand catch 44. Since the triangular plate 25 is now inclined downwardly toward the right, the weight 26 on the Z-shaped rod which supports the paint brush will swing to the dotted position of Figure 5 just prior to reversal of the oscillation of the arm 28. Thus the paint brush will remain inclined forwardly with respect to its direction of travel on the return stroke and its inclination will be reversed for the next painting stroke of the brush when the lever 51 strikes the left hand stop flange 53 as in the solid line position in Figure 3. This will permit the weight 26 to again swing downwardly after the right hand catch 44 has been released, thus automatically reversing the inclination of the paint brush.

70   During the forward stroke of the paint brush, the arm 41, through the pawl 42 engaging one of the lugs 43, will cause the color wheel 37 to advance simultaneously with the movement of the brush. Apparently therefore the brush paints out one color and paints in another color during

the forward stroke while during the return stroke the color remains the same. The brush thus traveling freely back and forth from side to side in the slot in the picture, constantly brushes the color sections on the color wheel and appears to produce a different color or paint a new strip across the picture each oscillation of the brush.

The movement of the brush and the color wheel are so timed relative to each other that the joint between adjacent color cards is hidden behind the bristles of the brush, thus giving the effect of the brush spreading on another color of paint during the right hand sweep of the brush. By making the stroke of the color wheel slightly longer than the stroke of the brush (the pivot 36a being further from the pivot axis than the pivot 36 to accomplish this result), the joints between color cards may be hidden beyond the ends of the slot 15a when the color wheel is at rest.

The realistic self motion of the brush simulating a life-like movement as if it was held in a painter's hand, readily attracts attention to the display as desired. The apparatus is so worked out however that the operating mechanism is entirely concealed from view and this, of course, enhances the spectacular quality of the display.

Some changes may be made in the construction and arrangement of the parts of my device without departing from the real spirit and purpose of my invention, and it is therefore my intention to cover by my claims, any modified forms of structure or use of mechanical equivalents, which may be reasonably included within their scope.

I claim as my invention:

1. In a paint advertising device, a display card, an arcuate slot therein, a color wheel back of said display card and spanning said slot, said color wheel having a plurality of different colors thereon which traverse said slot as said wheel rotates, a paint brush, means for supporting said paint brush in position with its bristles substantially contacting with said color wheel and its handle projecting away from said display card, said means being pivotally mounted whereby said brush may project at different angles relative to the surface of said display card, means for oscillating said paint brush supporting means, means for imparting pivotal movement thereto to reverse the angle of inclination thereof at the completion of each oscillation and means for periodically advancing said color wheel a portion of a revolution simultaneously with the oscillation of the paint brush supporting means in one direction, the length of the oscillating stroke of said paint brush supporting means being substantially equal to the degree of advance of said color wheel and the length of said different colors thereon being substantially equal to said degree of advance.

2. In a paint advertising device, a display card, an arcuate slot therein, a color wheel back of said display card and spanning said slot, said color wheel having a plurality of different colors thereon which traverse said slot as said wheel rotates, a paint brush, means for supporting said paint brush in position with its bristles in said slot and substantially contacting with said color wheel and its handle projecting away from said display card, said means being pivotally mounted, means for oscillating said paint brush supporting means, means for imparting pivotal movement thereto to reverse the inclination thereof relative to the surface of said display card at the completion of each oscillation of said brush

and means for periodically advancing said color wheel a portion of a revolution simultaneously with such oscillation.

3. In a paint advertising device, a display card, 5 an arcuate slot therein, a color wheel back of said display card and having a plurality of different colors thereon, a paint brush, means for supporting said paint brush in position with its bristles substantially contacting with said color wheel and its handle projecting away from said display card, said means being pivotally mounted whereby said brush may project at opposite angles relative to the surface of said display card, means for oscillating said paint brush supporting 10 means, means for imparting pivotal movement thereto to reverse the inclination thereof at the completion of each oscillation and means for periodically advancing said color wheel simultaneously with the oscillation of the paint brush 15 supporting means in one direction.

4. In an advertising device of the character disclosed, a background element having a slot therein, a movable element spanning said slot and having sections of different color, a paint 20 brush support, a paint brush supported thereby in front of said movable element with its bristles substantially contacting said movable element, means for advancing said paint brush support from one end of said slot to the other end thereof 25 and simultaneously therewith moving said movable element while the paint brush is on a dividing line between two of said sections of different color and for returning said paint brush support from said other end of said slot to said first end 30 thereof while leaving said movable element in its new advanced position and means for inclining said paint brush forwardly with respect to its direction of travel in either direction.

5. In an advertising device of the character disclosed, a background element having a slot therein, a movable element spanning said slot and having sections of different color, a paint brush support, a paint brush supported thereby, means for advancing said paint brush support 40 from one end of said slot to the other end thereof and simultaneously therewith moving said movable element while the paint brush is on a dividing line between two of said sections of different color and for returning said paint brush support from said other end of said slot to said first end 45 thereof and means for inclining said paint brush forwardly when traveling in either direction.

6. In an advertising device of the character disclosed, a background element, a paint brush support back of said background element, a paint 50 brush supported thereby with its bristles adjacent said background element, said support being concealed by said bristles and means for advancing said paint brush support across said background element and simultaneously therewith inclining said paint brush forwardly with respect to its direction of travel.

7. In an advertising device of the character disclosed, a background element, a paint brush support back of said background element, a paint brush supported thereby with its bristles adjacent 55 said background element, said support being concealed by said bristles and advancing said paint brush support back and forth across said background element and simultaneously therewith inclining said paint brush forwardly with respect to its direction of travel in either direction.

8. In a device of the class described, a sub-

stantially flat background element having a slot therein, a movable element back of said background element, said movable element having sections of different characteristics spanning said slot, a paint brush support having a pivotally mounted portion between said background element and said movable element, a paint brush supported by said paint brush support and projecting from said slot, means for reciprocating said paint brush support relative to said slot and for oscillating it at each end of its reciprocating movement and means for advancing said movable element with the movement of said paint brush support as it traverses said slot, the distance of advance and the length of a section thereof having one of said characteristics being slightly greater than the traverse of said paint brush.

9. In a device of the class described, a substantially flat background element having a slot 20 therein, a movable element back of said background element and spanning said slot, a paint brush support having a pivotally mounted portion between said background element and said movable element, a paint brush supported by 25 said paint brush support and projecting from said slot, means for reciprocating said paint brush support relative to said slot and for oscillating it at each end of its reciprocating movement and means for advancing said movable 30 element with the movement of said paint brush support as it traverses said slot.

10. In a device of the class described, a background element having a slot therein, a movable element back of said background element and 35 spanning said slot, a paint brush support back of said background element, a paint brush supported by said paint brush support and projecting from said slot, means for reciprocating said paint brush support relative to said slot and 40 means for advancing said movable element with the movement of said paint brush support as it traverses said slot in one direction, said last means permitting the movable element to remain stationary as the paint brush support 45 traverses said slot in the other direction.

11. In a device of the class described, a background member having a slot therein, an element back of said background member and spanning said slot, an inclined paint brush support oscillatable in said slot, a paint brush carried by said support and having said support embedded in its bristles, said bristles terminating in said slot against said element, means for reciprocating said paint brush support relative to said slot 50 and means for reversing the inclination of said paint brush support at each end of its movement as it traverses said slot.

12. In a device of the class described, a background element having a slot therein, a movable element back of said background element and spanning said slot, a paint brush support oscillatable in said slot, a paint brush carried by said support and having its bristles terminating in said slot against said background element, means for reciprocating said paint brush support relative to said slot for advancing said movable element with the movement of said paint brush support as it traverses said slot, said paint brush being inclined relative to said background element and means for reversing the inclination of said paint brush at each end of its stroke.
